UNITED STATES PATENT OFFICE.

FREDRICK WALZ, OF BURNSIDE, CONNECTICUT.

AUTOMATICALLY-CLOSING WRENCH.

Application filed January 3, 1923. Serial No. 610,544.

To all whom it may concern:

Be it known that I, FREDRICK WALZ, a citizen of the United States, residing at Burnside, in the county of Hartford and 5 State of Connecticut, have invented a new and useful Improvement in Automatically-Closing Wrenches, of which the following is a specification.

This invention relates to the type of quick 10 closing wrenches. These wrenches have a spring arranged to force the movable jaw toward the fixed jaw when a locking stem is released by pressure of the thumb on a locking plunger which normally engages the 15 locking stem and holds the movable jaw fast, whereby in order to apply the wrench to a nut or bolt or other part to be held or turned, it is only necessary to open the jaws, hold them adjacent to the element 20 to be gripped and then press inwardly the locking plunger and allow the spring to close the jaws on the part.

The object of the present invention is to provide a very simple, cheap and strong 25 construction which is easily and conveniently manipulated and which has a fine adjustment.

In the accompanying drawings Figure 1 shows the invention embodied in a structure 30 having jaws of the monkey wrench type. Fig. 2 shows a top view of the same. Fig. 3 shows a section on the plane indicated by the dotted line 3—3 on Fig. 1. Fig. 4 shows the wrench head with ninety 35 degree jaws and one hundred and twenty degree jaws. Fig. 5 shows the head with ninety degree jaws and pipe gripping jaws.

The handle 1 of the wrench is desirably made of metal but can be formed of other 40 suitable material. The fixed jaw 2, which may have a ninety degree face or a one hundred and twenty degree face or pipe teeth or combination of these as illustrated in the views, is connected with the handle 45 in the embodiment illustrated by a pair of rods 3 that pass through perforations in the jaw and into sockets in the end of the handle. These rods may be circular in cross section and may be cut from what is known 50 as drill rod. A pin 4 is driven through the fixed jaw between the rods, and a pin 5 is driven through the handle between the rods for securing them in place. The only 55 machining required for such an attachment of these parts is accomplished by mere drilling.

The movable jaw 6 fits and slides upon the rods that join the fixed jaw and the handle. A locking stem 7 is fastened to the movable jaw and it extends into a longitudinally extending bore 8 in the handle. This stem is provided with fine teeth 9 which desirably are in the shape of screw threads. Back of the locking stem in the bore in the handle is a spring 10 arranged 60 to thrust the stem outward. The spring is held in by a screw plug 11 threaded into the bore at the end of the handle after the spring has been placed in the bore. The locking stem passes through an opening 12 in a locking plunger 13 which is free to 65 slide in a transverse bore in the handle. The opening in the plunger is somewhat larger than the diameter of the locking stem and on the inner wall has teeth 14 shaped 70 to fit the teeth of the locking stem. A spring 15 is arranged in the transverse bore in the handle to normally push the plunger 75 outward and cause the teeth on the wall of the opening through the plunger to engage the teeth on the locking stem. When the plunger is pushed inward the teeth are disengaged releasing the stem and permitting the spring to thrust the stem outward 80 and carry the movable jaw toward the fixed 85 jaw against anything placed between the jaws that it is desired to grip. When pressure on the plunger is released its teeth engage the teeth on the stem and lock the parts so that the movable jaw cannot be 90 moved from its position. The teeth on the locking stem are quite fine so that the adjustment of the movable jaw will be close. The elements of this structure are very simple 95 to manufacture and assemble. It is easy to release the locking stem and allow the spring to close the movable jaw, yet when the locking plunger is engaged with the locking stem the movable jaw is very strongly held. This wrench can be manipulated 100 and applied to a nut, bolt head or other part to be held or turned, by one hand.

The invention claimed is:

1. A wrench having a handle with a longitudinally extending bore and a circular 105 socket extending transversely across said bore, a fixed jaw, means connecting the fixed jaw with the handle, a movable jaw sliding on said connecting means, a circular threaded rod extending from the movable jaw in 110 front of said connecting means into and substantially fitting the bore in the handle, a

spring arranged in said bore and adapted to thrust the rod outward, a cylindrical plunger located in the transverse socket in the handle, said plunger having a transverse opening through which the threaded rod extends, the inner wall of said opening having teeth, and a spring in the socket thrusting the plunger outward and causing the engagement of the teeth on the wall of the opening through the plunger with the threaded rod.

2. A wrench having a handle, a pair of round rods with their ends extending into round openings in the handle, a jaw with round openings fitted on the outer ends of said rods, a pin extending transversely of the handle between the rods and a pin extending transversely of the jaw between the

rods for locking the rods to the handle and the jaw to the rods, a movable jaw slidably fitted on said rods between the handle and fixed jaw, a threaded rod extending from the movable jaw in front of the connecting rods into a longitudinal bore in the handle, a spring in the bore in the handle and adapted to normally thrust the threaded rod outward, a plunger located in a socket that opens through the front edge of the handle, said plunger having an opening through which the threaded rod passes and having teeth in one wall of said opening, and a spring normally thrusting the plunger radially of the threaded rod and causing the engagement of the teeth.

FREDRICK WALZ.
